UNITED STATES PATENT OFFICE.

JUNIUS R. WILLCOX, OF NORFOLK, VIRGINIA.

DESIGN FOR A BADGE.

No. 37,514.

Specification for Design.

Patented Aug. 29, 1905.

Application filed May 3, 1905. Serial No. 258,735. Term of patent 7 years.

To all whom it may concern:

Be it known that I, JUNIUS R. WILLCOX, a citizen of the United States, residing at Norfolk, in the county of Norfolk and State of Virginia, have invented a new, original, and ornamental Design for a Badge, of which the following is a specification.

My invention relates to badges.

The drawing shows a plan view.

I claim—

The ornamental design for a badge as shown.

JUNIUS R. WILLCOX.
